ARTHUR H. LABISKY AND OTTO E. ZAHL, OF WEST BEND, WISCONSIN, ASSIGNORS TO THE BARTON CORPORATION, OF WEST BEND, WISCONSIN, A CORPORATION OF WISCONSIN

WASHING MACHINE

Application filed March 3, 1928. Serial No. 258,703.

This invention relates to washing machines, and one of its objects is to increase the efficiency of power operated washing machines. Another object is to provide improved transmission gearing between the motor and the clothes agitating means, and the wringer. Another object is to provide transmission gearing in which all of the shafts thereof extend in vertical lines and the gears lie in horizontal planes. Another object is to provide a novel dolly or agitator shaft assembly of improved construction and arrangement. Another object is to provide improved clothes agitating means constructed and arranged to prevent injury to the clothes and to prevent the clothes from becoming tangled around the dolly shaft.

Other objects and advantages will appear in the course of the specification, and with all of said objects and advantages in view, said invention consists in the several novel features of construction, arrangement and combinations of parts hereinafter fully set forth and claimed.

The invention is clearly illustrated in the drawings accompanying this specification in which—

Figure 1 is a side elevation of a washing machine partly broken out and illustrating a simple embodiment of the present invention;

Fig. 2 is a view, partly in plan and partly in horizontal section, taken on the line 2—2 of Fig. 1;

Fig. 3 is a detail plan of a clothes agitator;

Fig. 4 is a detail plan of the dolly;

Fig. 5 is a plan of the gear case and transmission gearing with the upper section of the gear case removed;

Fig. 6 is a detail vertical cross section taken on the line 6—6 of Fig. 5;

Fig. 7 is a detail vertical cross section taken on the line 7—7 of Figs 5 and 8, with certain parts broken out;

Fig. 8 is a detail vertical longitudinal section taken on the line 8—8 of Fig. 2;

Fig. 9 is a detail vertical section of the dolly taken on the line 9—9 of Fig. 4;

Fig. 10 is a detail side elevation of an agi-

tator supporting sleeve of the dolly shaft assembly; and

Fig. 11 is a plan of the sleeve shown in Fig. 10.

Referring to said drawings, which illustrate a simple embodiment of the present invention, the reference character 12 designates the supporting frame of the machine, which frame may comprise upright frame members 13 connected to horizontal frame members, such as rings or bands, 14 and 15, so as to provide a rigid and substantial supporting frame for the mechanism of the machine. The frame members are preferably composed of channel formation in order to obtain strength and lightness.

Supported upon the horizontal frame member 14 is the tub 16 in which is contained the clothes agitating devices, here shown as comprising an agitator 17, located adjacent the bottom of the tub and a dolly 18 positioned above the agitator. The dolly and agitator are mounted on a dolly shaft 48, oscillated by novel transmission gearing located below the tub and driven from an electric or other motor 19, which may be supported on a bracket 19^a mounted on the frame-work of the machine.

The transmission gearing is contained within a gear case 20 preferably composed of an upper section 21 and a lower section 22 bolted or otherwise secured together along their contacting marginal edges. The gear case is supported by the frame of the machine, and, as shown, it is provided with up-standing lugs or brackets 23 and 24, the lug 23 being bolted or otherwise secured to the band or ring 14, and the lugs 24 being bolted or otherwise secured to a brace bar 25 which is secured to the band or ring 14. The gear case lies in a horizontal plane and contains the transmission gearing, the shafts of which extend in vertical line, while the gear wheels and other power transmitting elements lie in and move in horizontal planes, whereby the use of mitered or beveled gears is entirely eliminated.

Referring now to Figs. 5, 6 and 8, which illustrate the transmission gearing in detail, it will be seen to comprise, among

other things, a spur gear wheel 26 having a vertical stud shaft 27 secured thereto and journaled in a bearing formed in a boss 28 on the lower side of the lower gear case section 22. The spur gear wheel 26 is preferably formed with a hub portion which is contained in a recess in the gear case and rests on the bottom of said recess.

Meshing with the spur gear wheel 26 is a spur pinion 29 which is pinned to a short vertical shaft 30 journaled in bosses formed in the upper and lower gear case sections. The shaft 30 protrudes from the upper gear case section, and upon the protruding end 10 is pinned or otherwise secured a belt pulley 31 over which is trained a belt 32 which runs to a belt pulley 33 secured on the vertical shaft of the motor 19. The spur gear wheel 26 and pinion 29 are preferably contained in the lower section of the gear case, and directly above said spur gear wheel and pinion is a rocker arm or oscillating arm 34 which, as shown, is fulcrumed upon an axis concentric with the axis of the wringer driving shaft shown at 35. Said wringer driving shaft extends in a vertical direction along the side of the tub and is provided at its upper end with suitable gearing (not shown) for operating the wringer, but inasmuch as said wringer driving gearing forms no part of the present invention, it has not been illustrated.

A horizontal spur gear wheel 36 is provided for rotating the wringer driving shaft 35, and said spur gear wheel intermeshes with the spur gear wheel 26. The spur gear wheel 36 has a vertical, downwardly extending stud shaft 37 secured to it, which is journaled in a boss 38 formed on the lower section 22 and on the upper side of the spur gear wheel it is formed with an upstanding hub portion 39 which is journaled in a boss on the upper gear case section. The hub portion 39 acts as the fulcrum for the rocker arm 34 which is apertured at one end to receive the hub portion. Suitable driving connections are provided between the hub of the spur gear wheel 36 and wringer driving shaft 35, and, as shown, said connections comprise a clutch pin 40 secured in the wringer driving shaft 35 and entering in notches formed in the upper end of the hub portion 39. A sleeve or casing 41 is secured in the boss on the upper gear case section and extends up to the housing (not shown) for the gears of the wringer mechanism.

The rocker arm 34 rests upon the spur gear wheels 26 and 36, and oscillates in a horizontal plane, and means are provided for oscillating said rocker arm, which means, as shown, comprise a wrist pin 42 secured in the hub portions 43 of the spur gear wheel 26 and traveling in a slot 44 formed in the rocker arm 34. As a preference, a slide block 45 is provided upon the wrist pin and

slides in the slot of the rocker arm. Upon the free end of the rocker arm is a gear segment 46 which meshes with a spur pinion 47, loosely mounted upon the dolly shaft 48 which is journaled in a boss 49 formed on the lower gear case section 22.

The spur pinion 47 and dolly shaft 48 are provided with co-acting clutch jaws 50 and 51, whereby the pinion and dolly shaft may be clutched together or unclutched from each other. The clutch jaws 50 are preferably formed on a grooved clutch collar 52 pinned or otherwise secured to the dolly shaft and arranged for engagement with a clutch lever 53 fulcrumed in an upstanding housing 54, formed on the upper gear case section 21 and surrounding the clutch mechanism.

Removably secured to the upper end of the housing 54 is a sleeve 55 which functions as a bearing for the upper end of the dolly shaft 48. As illustrated in the drawings, the lower end of the sleeve 55 is formed with a shouldered portion 56 and with a threaded part 57 which screws into a threaded opening in the upper end of the housing 54. The bottom 58 of the tub is secured between the shoulder 56 of the sleeve 55 and the upper end of the housing 54, and gaskets 59 are provided between the tub bottom 58, the shoulder 56 and the housing 54 to make a leak proof joint at this point. An outwardly opening chamber 60 is formed in the housing 54 below the lower end of the threaded part 57 of the sleeve 55, and in said chamber is a cone shaped disk 61 of rubber or the like, which disk fits snugly upon the dolly shaft 48 and acts to shed any water trickling down along the dolly shaft, away from the mechanism below the disk.

Rotatably mounted upon the bearing sleeve 55 is a supporting member 62 for the dolly and agitator, here shown in the form of a sleeve projecting above the bearing sleeve 55 and having its upper end pinned or otherwise secured to the upper end of the dolly shaft 48, whereby the oscillatory movements of the dolly shaft are imparted to said supporting member 62. The agitator 17 is removably mounted upon the supporting member 62. As shown, the supporting member 62 is formed at its lower end with a shoulder 63 upon which the agitator rests, and the supporting member is formed with a plurality of grooves 64 in its face that are adapted to receive lugs or other projections 65 formed on the agitator, whereby the latter is connected to the agitator supporting member so as to oscillate therewith, but capable of being readily removed therefrom by lifting it up above the dolly shaft.

The agitator is of novel construction. It is composed of a flaring or bell shaped body portion, the lower marginal edge portion 130

of which lies adjacent the bottom of the tub, while the upper end is in the form of a sleeve or collar portion 66 which surrounds the agitator supporting member. On the underside of the flaring or bell shaped part of the agitator is formed a downwardly projecting sleeve or collar 67 which also surrounds the agitator supporting member, both of said sleeves forming a long bearing or connection between the agitator and its supporting member, thereby preventing any tendency for the agitator to tilt upon its support.

On the upper face of the body portion of the agitator are radial ribs 68, which by preference upstand only slightly and merge into the face thereof at places adjacent its upper end. Said ribs which engage the clothes cooperate with a dolly, presently to be described, in propelling them back and forth in the tub during the washing operation. It will be understood that the clothes, which are being washed, rest in part upon the agitator so as to be carried by it back and forth, around the interior of the tub. The walls of the body portion, sleeves and ribs may be formed of relatively thin, light weight material, such as aluminum, if desired.

Associated with the agitator is the dolly 18, which is also removably held on the agitator supporting member 62. As shown, the dolly has a concavo-convex, or dished disk-like body portion 69 which extends from a central hub portion 70 that surrounds the agitator supporting member and is formed with lugs or tongues 71 which engage in the grooves 64 of the agitator supporting member. On the lower convex side of the dolly are downwardly projecting radial lugs 72 which engage with the clothes and act to propel them back and forth in the interior of the tub. If desired, the lugs may be cast hollow, as shown, for the sake of lightness, and a number of apertures 73 are formed in the body of the dolly to permit water to pass through the same. The dolly may be formed of cast light weight material such as aluminum, if desired.

Conveniently, one or more knobs 74 are secured to the disk-like portion of the dolly and furnish means whereby the same may be handled in placing it upon the agitator supporting member or removing it therefrom, or in case it is desired to turn the dolly and agitator manually. It is to be understood that the dolly is slidably connected with the agitator supporting member and is free to move up and down thereon. Fig. 8 of the drawings shows the dolly as suspended, which is a position occupied by it when resting upon a batch of clothes contained in the tub. When placing clothes in the washing machine or removing them therefrom, the dolly may be disconnected

from the agitating supporting member and afterwards replaced. When clothes are contained in the tub the dolly rests upon the clothes, but when the clothes are removed it rests upon the upper end of the agitator.

From the above it will be observed that all of the toothed members of the transmission gearing are arranged in horizontal planes with their shafts extending in vertical lines, whereby the use of beveled or mitered gears is entirely eliminated. Furthermore, the arrangement of the vertical shafts permits the motor shaft to extend vertically which is of particular importance. By arranging the fulcrum of the rocker arm 80 concentric with the wringer driving shaft, a relatively long rocker arm is obtained, and by placing the rocker arm actuating wrist pin intermediate the ends of the rocker arm a long sweep is given to the rocker arm with 85 a very steady and even motion. With the long sweep of the rocker arm, the dolly and agitator are moved through the greater part of a complete circle.

It is also to be observed that by reason 90 of the novel disposition of the power transmitting elements, the oscillatory member thereof is operatively connected to the dolly shaft without the interposition of any bevel or miter gears and one of the continuously 95 rotating power transmitting members is operatively connected to the wringer driving shaft without the interposition of any bevel or miter gears. The novel dolly shaft assembly enables the parts to be readily assembled in constructing the machine and permits the ready removal and replacement of the dolly and agitator. The bell shaped or flaring agitator, while acting as a support for the clothes, prevents them from becoming tangled around the dolly shaft. If desired, however, the agitator may be dispensed with, in which case, the clothes rest upon the bottom of the tub. The dolly being freely mounted upon the supporting sleeve, 100 it rests upon the clothes during the washing operation and the depending lugs thereon enter among the clothes and carry them around back and forth through the water during the washing operation.

It is believed that the operation of the machine is readily apparent from the above description. Briefly, the motor being put into operation, the spur gear pinion 29 is rotated through the instrumentality of the 115 pulleys 33 and 21 and belt 32 and the spur gear wheel 26 is thereby rotated at a reduced speed. As the spur gear wheel 26 rotates, the wrist pin 42 is rotated in the slot 44 of the rocker arm 34, and, as a consequence, the rocker arm is oscillated, thereby imparting a rotary reciprocating or oscillatory movement to the spur pinion 47. Inasmuch as the spur gear wheel 36 for the 120 wringer driving shaft 35 intermeshes with 125

the spur gear wheel 26, the wringer driving shaft is continuously rotated during the operation of the transmission gearing. By properly shifting the clutch lever 53, the 5 dolly shaft 48 may be clutched to the spur pinion 47 or unclutched therefrom as desired, and, in this way, the operation of the agitator and dolly may be controlled.

It will be observed that the clothes are 10 supported, at least in part, by the agitator and that the dolly rests upon and engages with the clothes. The agitation of the clothes is accomplished by the dolly with the clothes resting upon the agitator. The 15 clothes, being confined between the agitator and dolly, are carried back and forth through the water in the tub, whereby a very thorough washing action is obtained on the clothes. Furthermore, this arrangement 20 prevents the clothes from being tangled and also provides means for agitating the clothes throughout the depth of the tub, since the agitator co-operates with the dolly in swinging the clothes back and forth in the tub. 25 By the term "agitator", wherever used in the specification and claims, is meant a support for the clothes operatively connected with the dolly shaft so as to rotate therewith.

30 More or less variation of the exact details of construction is possible without departing from the spirit of this invention. We desire, therefore, not to limit ourselves to the exact form of the construction shown 35 and described, but intend, in the following claims, to point out all of the invention disclosed herein.

We claim:

1. In a washing machine, transmission 40 gearing comprising a power driven horizontally disposed spur gear wheel, a second spur gear wheel meshing with said power driven spur wheel and having a hub portion arranged to rotate a wringer driving 45 shaft, a horizontally disposed rocker arm having a gear segment on one end and fulcrummed upon the hub of said second named spur gear wheel, and formed with a slideway extending longitudinally of the 50 arm, there being a wrist pin on said spur gear wheel traveling in said slideway, and a horizontally disposed spur pinion meshing with said gear segment, in combination with 55 a vertical dolly shaft operatively connected with said spur pinion.
2. In a washing machine, the combination 60 of a tub, a vertical motor, transmission gearing comprising power transmitting elements, disposed and moving in horizontal planes, and including a horizontal rocker arm, a gear segment, and a spur pinion meshing with said gear segment enclosed in a housing below the tub, a vertical oscillatory dolly shaft extending into said tub and

housing, and a clutch mechanism between said dolly shaft and spur pinion.

3. In a washing machine, the combination of a tub, a motor, transmission gearing driven by said motor and comprising power transmission elements disposed below the tub in horizontal planes, a housing for said elements, a dolly shaft extending into said tub and housing, a clutch mechanism connecting said elements and shaft, and a convex washer on said shaft and overhanging said clutch mechanism for shedding water away therefrom.

4. In a washing machine, the combination 80 of a tub, a motor, power transmitting gears operated by said motor and disposed below the tub in horizontal planes, a vertical stub shaft carrying one of said gears, a vertical dolly shaft extending into the tub, a manually operable clutch connecting said stub and dolly shafts whereby the power transmitting gears may be separated at the clutch connection as a unit from the tub.

5. In a washing machine, the combination 90 of a tub, a motor, power transmitting gears operated by said motor and disposed below the tub in horizontal planes, a vertical stub shaft carrying one of said gears, a vertical dolly shaft extending through and below the tub, a clutch connecting said stub and dolly shafts whereby the power transmitting gears may be separated at the clutch connection as a unit from the tub.

ARTHUR H. LABISKY.
OTTO E. ZAHN.
